DESIGN FOR A BEVERAGE SET

Edward Kanter, Cleveland Heights, Ohio

Application December 1, 1933, Serial No. 49,909

Term of patent 7 years

To all whom it may concern:

Be it known that I, EDWARD KANTER, a citizen of the United States, residing at Cleveland Heights, in the county of Cuyahoga and State of Ohio, have invented a new, original, and ornamental Design for a Beverage Set, of which the following is a specification, reference being had to the accompanying drawing, forming part thereof, wherein Fig. 1 is a perspective view; Fig. 2 is a side elevation and Fig. 3 is a top plan view of a beverage set showing my new design.

The cylindrical elements beneath the base and the peg like elements protruding upwardly from the base are permanently fixed and constitute a distinct and permanent part of the entire design.

I claim:—

The ornamental design for a beverage set substantially as shown and described.

EDWARD KANTER.
